Frank Marion,

By **H. S. Woodward,**

Attorney

UNITED STATES PATENT OFFICE.

FRANK MARION, OF BARRE, VERMONT, ASSIGNOR OF ONE-HALF TO ELWIN L. SCOTT,
OF BARRE, VERMONT.

ELECTRICAL HEATING DEVICE.

Application filed March 2, 1926. Serial No. 91,793.

- The invention relates to electrical heating apparatus, and has for an object to provide a novel construction in means for applying and conserving heat generated electrically.
- 5 It is a particular purpose to evolve means for efficiently heating stoves, furnaces, and for heating and vaporizing liquids. Specifically, in the present embodiment of the invention, it is adapted to the vaporization of 10 water, in such manner as to supply steam to a heating system, and it may be used as an auxiliary to an ordinary coal burning boiler and circulation system, or as the sole vaporizing unit for such a system.
- 15 It is a specific purpose in the present showing to evolve a readily constructed and easily assembled vaporizer or heater unit, adapted to be produced at low cost, and which may be easily installed, and maintained. It is an object to provide novel features in the parts, adapted to increase the efficiency of the apparatus and facilitate assembly and repair.
- 20 It is an object to present a novel heat diffusing unit in such devices.
- It is also a purpose to coordinate a heater unit of this kind with a boiler and heating system in a novel manner.
- Additional objects, advantages and features of invention reside in the construction arrangement and combination of parts as will be understood from the following description and accompanying drawings, where-in—
- 25 Fig. 1 is a longitudinal sectional view of one embodiment of the invention.
- Fig. 2 is a view of the left end of the diffuser unit removed.
- Fig. 3 is a view of the water chamber from the open end.
- 30 Fig. 4 is a diagrammatic showing of the use of this device as an auxiliary in a steam heating system or hot water heating system.
- Fig. 5 is a detail elevation of a coil assembly adapted to the uses indicated.
- 35 There is illustrated a cylindrical chamber body 10, adapted to be cast in metal, one end being closed by an integral head 11, while a removable head 12 is bolted snugly upon the opposite end, the wall 13 opening flush at the end and being suitably thickened to receive this plate and the bolts by which it is secured. This chamber is jacketed by an 40 enclosure 14 of suitable material after approved methods for conserving heat within the chamber 10. In the present instance the jacket is spaced from the chamber body so as to form a dead air space, and if desired a pipe 15 may be led off from the top of the jacketing to convey hot air therefrom for 45 utilization as desired. The chamber 10 is fitted with a water gauge 16 of ordinary construction; a safety valve 17 is incorporated when the device is used independently of a steam boiler; mercury and pressure gages 50 18 and 19 are also installed, while a water supply connection and a drain cock are shown at the bottom of the chamber.
- At the top of the chamber a steam outlet pipe 20 is shown, adapted to serve as the 55 riser in a piping system for heating, and at the bottom a pipe 21 leads into the chamber, to be used as the return of such a system.
- The head 12 is centrally thickened and formed with an axial opening through 60 which there is projected from within the chamber the tubular neck 24 of a bellows-like heat diffuser 25, preferably formed of a metal or other material of high heat transmission efficiency, nickel-chromium steel 65 alloy being one that may be used, it being desirable that the material be also sufficiently refractory to resist heat properly for the purposes contemplated. This diffuser is formed with a multiplicity of hollow disk-like members 26 connected by reduced necks 70 75 80 85 90 95 100 105 110 formed integrally therewith, or otherwise, so as to form one hermetically sealed chamber throughout the series of members 26. The outer walls of the end members 26 are thickened to enable the ready support of the diffuser within the chamber 10 by coengagement between the body of the chamber and these walls. On the head 11 of the chamber 10 there is formed a ledge 28 having an upper side adjacent the longitudinal axis of the chamber 10, while the adjacent wall of the diffuser is formed with a lug 29 adapted to rest upon the ledge for support of the diffuser at its inner end. At the opposite end the diffuser is secured by bolts 30 engaged through the head 12 and these serve also to secure centrally the adjacent end element of the jacket 14, a ring 31 being clamped thereagainst by the bolts.
- The neck portions 27 have an interior diameter corresponding to that of the neck 24, whereby an electrical coil assembly may be introduced slidably from one end through the diffuser, as will be described. The inner

end wall of the diffuser is formed with an axial knob or lug projecting inwardly within the diffuser, and this is inserted in the end of a tube 32 upon which there is a porcelain cylinder, having exterior spiral groove in which there is laid a heater coil 33. The outer end of the tube 32 is mounted in a cap plate 34 by which the mouth of the neck 24 is closed, the porcelain stopping short of this plate, and a packing 35 of heat-insulating material is provided within the neck between the porcelain cylinder and the cap plate. Through the plate 34 a wire 36 is led with suitable bushing to the adjacent end of the heater coil 33, while from the inner end of the coil 33 a wire 37 is led inward through the porcelain and through the tube 32 outward and through the outer end of the tube, as shown.

20 When the appliance is to be used as the sole heating element for a system, it may be mounted in any convenient location suitable for the purpose. When used as an auxiliary to a steam boiler, advantage may be taken 25 of cooperation between my appliance and the regular boiler in maintaining the water supply safely and efficiently within the proper limits. That is to say, the chamber 10 and assembled parts is preferably mounted 30 at such height with respect to the regular boiler 40, that the normal water level in such boiler, as indicated by the dotted line in Fig. 4, will be closely adjacent the upper edges of the elements 26 of the diffuser 25. The boiler 40 will serve as an automatic replenishing means for the appliance as water 35 is vaporized, avoiding liability of excessive exhaustion of the water content. In case my apparatus is used as an independent heating 40 source a reservoir corresponding to the boiler 40 in horizontal dimension may be employed after the manner illustrated but the lower part of such reservoir need not of course extend as low as the boiler shown, and may be of less depth than the chamber 45 10, the large horizontal extent as compared to the chamber 10 being the principal element to be embodied along with the relative arrangement indicated.

50 In Figure 5, there is illustrated a modification of the mounting of the heater coil, adapted specially for use as an insertable element in diffusers such as here shown, or in fireboxes of stoves and furnaces and heaters of various kinds. In this instance, a cylindrical porcelain core 50 has mounted thereon a multiplicity of thin sheet metal discs 51 of a metal adapted to be heated readily to incandescence, these discs are stamped from sheet metal with laterally 60 turned outer edges 52 in a groove shape, adapted to permit the laying of a heater coil thereon for retention of one convolution on each disc. The central portion of the disc is also extruded laterally to form a hub flange 53 fitting snugly the porcelain core. The discs are spaced apart by small porcelain rings. The outer parts of the discs are coated with porcelain enamel or the like, or other insulation resistant to the heat 70 which may be expected. This mounting provides for an intimate circulation of air or other fluid or liquid within and around the heater coil so that a maximum of heating efficiency is gained when it is energized. 75 The core may be constructed in various ways for mounting in the various situations where required for use.

I claim:

1. In a device of the character described, a liquid containing chamber, closed at one end and having an interior rest at its inner end, a removable head secured on the opposite end, and a hollow diffuser secured to the removable head longitudinally slidable in the chamber and removable with the head, said diffuser having a lug at its extremity adapted to engage said rest for support. 80
2. A heater unit comprising a core of non-conducting material, a multiplicity of thin sheet-metal discs in mutually insulated spaced relation mounted thereon, and a heater coil having respective convolutions each in the form of a helix having an annular axis and peripherally carried by a respective disc aforesaid in intimate heating relation thereto. 85
3. A heater unit comprising a core of non-conducting material, a multiplicity of thin sheet metal discs in mutually insulated spaced relation mounted thereon, and a heater coil having respective convolutions mounted in intimate relation to respective discs, each disc being formed with a peripheral coil-retaining groove. 90
4. The structure of claim 3 in which each disc is formed with laterally turned edge portions shaped to form a peripheral groove. 100
5. The structure of claim 3 in which the discs are slidable on the core and small insulating washers interposed between the discs. 110
6. The structure of claim 3 in which each disc is formed with a peripheral coil-retaining groove. 115

In testimony whereof I affix my signature.

FRANK MARION.
